THOMAS WADGE AND BERNARD JOSEPH DESMOND, OF WINNIPEG, MANITOBA,
CANADA.

SHOCKING MACHINE.

Application filed April 15, 1922. Serial No. 553,059.

The invention relates to improvements in shocking machines, and an object of the invention is to provide a machine which will accompany the customary binding machine on the field and will receive sheaves ejected from the binding machine deck, elevate and deposit the sheaves ejected, into a shock former and then subsequently deposit the formed shock on the field in a standing position and firmly plant it.

A further object of the invention is to construct a machine which is entirely automatic in its action and is directly under the control of the attendant on the binding machine.

A further object is to construct a machine which forms the shock in a substantially horizontal position and then controls the shock until it is firmly planted in a standing position on the field.

A still further object of the invention is to provide a machine wherein the shock is not positively dropped to plant it on the field, but is built low to the ground, and then is whilst under complete control, upended on to the ground by a rolling movement which swings the butt of the shock into the stubble and whilst retaining the shock in a stationary position in respect to the ground and permitting the machine to move away from it as the machine advances with the binder.

A further object is to arrange various parts associated with the shock during the planting action in such manner that the momentum of the shock is entirely overcome.

A further object is to firmly hold the heads of the sheaves together and also to spread the bases thereof to insure of a large butt to the shock and also to generally construct various working parts so that there is no tendency to thresh the heads of the sheaves.

A further and more detailed object is to provide an improved form of butter coacting with the basket which can be adjusted to accommodate the grain, that is, long, short, or intermediate sheaves and to associate with the butter, a kicker which will act to move the sheaves entering the basket to the sides.

A still further and more specific object is to provide the basket with a pivoted and controlled bale bar on which the heads of the inserted sheaves are built and which acts

initially to draw the heads of the sheaves together in the forming of a shock and subsequently to maintain the heads together up to, and subsequently to the time that the shock is deposited.

Fig. 1 is a plan view of the machine with the sheaf former or basket in the sheaf receiving position.

Fig. 2 is a side view of the machine.

Fig. 3 is a front view thereof.

Fig. 4 is a longitudinal vertical sectional view at 4—4' Figure 1 centrally through the machine, certain parts being shown in side elevation.

Fig. 5 is a plan view of a portion of the machine frame work and showing certain operating parts.

Fig. 6 is a side view of the basket removed from the machine.

Fig. 7 is a rear view of the basket removed from the machine.

Fig. 8 is a vertical sectional view at 8—8' Fig. 5 and looking towards the ground wheel.

Fig. 9 is an enlarged detailed vertical sectional view at 9—9' Fig. 2.

Fig. 10 is an enlarged detailed vertical sectional view at 10—10' Fig. 1.

Fig. 11 is an enlarged detailed plan view of the small end of the basket.

Fig. 12 is an enlarged vertical sectional view at 12—12' Fig. 5.

Fig. 13 is a perspective view showing the double winged guards and parts associated therewith.

In the drawings like characters of reference indicate corresponding parts in the several figures.

The machine is adapted to be hitched to the customary binding machine at the deck side thereof and is drawn by the binding machine as the same is advancing on the field.

The sheaves ejected from the binding machine deck are caught by the elevator of the shocking machine and directed by it to the basket or shock former and there formed into a shock which is subsequently deposited on the ground.

As the arrangement of shocking machines in respect to a binding machine is well known we have not considered it necessary to show the binding machine, other than the deck which discharges the sheaves onto the shocking machine elevator.

The deck is indicated by the reference numeral 1, Figure 3, and this is the only figure in which any part of the binding machine is shown.

- 5 The main frame 2 of the shocking machine comprises a pair of outer parallel rearwardly extending side beams 3 and 4 and a pair of inner parallel side beams 5 and 6, the inner beams being spaced from 10 the outer beams and having their forward and rear ends permanently riveted to the outer beams which are bent in the manner best shown in Figures 1 and 5. It will be observed that the forward ends of the beams 15 3 and 4 converge forwardly and have their forward meeting ends elevated and that a bearing 7 is formed to receive swivelly the pivot pin 8 of a centrally positioned forwardly disposed castor wheel 9.
- 20 A pair of parallel spaced cross beams 10 and 11 connect the side beams forwardly, and comparatively short cross beams 12 and 13 extend between the rear portions of the beams 3 and 6 and 4 and 5 respectively.
- 25 Intermediate lengthwise extending beams 14 and 15 are carried by the frame and the intermediate beams and the inner beams support more or less centrally of their length angle plates 16 and 16', said angle plates 30 being directly opposed to similar angle plates 17 and 17' secured to the beams 3 and 4. The angle plates are really pairs of bearing brackets which support rotatably short shafts 18 and 18' on which we mount 35 ground wheels 19 and 19', the wheel 19 being provided with a comparatively wide traction rim and being utilized for driving purposes.

From the above arrangement it will be 40 apparent that the shocking machine frame is in reality a double substantially rectangular frame having an open rear end and carried forwardly by a castor wheel and rearwardly by two ground wheels.

45 We might point out, also, at this time that the shocking machine frame is mounted such that it is relatively close to the ground, this being different from the usual shocking machine frame which is quite well elevated 50 from the ground. The reason for this will be later apparent.

To the inner beams 5 and 6 of the shocking machine frame, which beams in reality are heavy angle irons (see Fig. 10) we permanently secure similar tracks 20 and 21, 55 said tracks being of channel iron cross section, with the upper edges of the channel irons fitted with inturned flanges 22 and 22'. These tracks are parallel and extend horizontally forwardly from the rear ends of the beams 5 and 6 to a point somewhat in advance of the ground wheels. They are then turned upwardly to provide arcuate forward track extensions 20' and 21'. The 60 forward extensions are suitably braced from

the frame structure by angular brace bars 23 and 23' extending to the frame and the angle braces form a support for the rear end of a forwardly located and horizontally disposed elevated frame work 24 utilized for 70 supporting parts later described.

The basket or sheaf former 25 is more or less of an inverted V-shape and it is carried by suitable rollers or travellers operating in the tracks 20 and 21.

75 The basket body is formed from a pair of V-shaped frames 26 and 27, these frames being positioned one above the other and converging rearwardly and having their rear ends connected together by a tie beam 28 of 80 predetermined length. Tie bars 29 and 29' connect the forward ends of the V-shaped frames, and the upper V frame is reinforced by a rearwardly positioned angle bar 30. The sides of the basket are enclosed by sheet 85 metal side plates 31 and 31'.

The forward corners of the basket are provided with legs 32 and these legs are fitted with rollers or carriers 33 mounted within the tracks, the legs actually passing 90 into the tracks between the flanges 22 and 22' hereinbefore described.

95 From the above arrangement it will be apparent that the basket is confined in its movement by the tracks and normally or in the sheaf receiving position thereof it is positioned forwardly and maintained in the position as best shown in the several principal figures of the drawings.

100 It might here be noted that a pair of opposed single rollers is used to carry the upper or forward part of the basket and two spaced pairs of rollers are utilized to carry the lower part of the basket. These rollers are best shown in Figures 6 and 7.

105 The basket is moved by similar operating bars or rods 34 and 34', the said rods having their rear ends pivotally connected to the forward lower corners of the basket at 35 and their forward ends pivotally mounted on pivot pins 36 and 36' carried by endless side chains 37 and 37'. These side chains are carried at each side of the machine by a forward chain wheel 38 and a pair of rear chain wheels 39 and 40, the chain wheels 40 being located above those 39 so that there is a portion of each chain travelling in a vertical direction between the chain wheels 39 and 40.

110 The chain wheels 38 are permanently mounted on the ends of a counter shaft 41 rotatably carried by the frame 24 and the chain wheels 39 and 40 are rotatably mounted on stub shafts 39' and 40' carried by vertically extending bars 42 and 42' provided as part of the machine frame structure.

115 Obviously, by driving the shaft 41 the side chains will be operated and the pins 36 will be caused to travel with the chains in what 120

might be termed a triangular path having a vertical component.

The forward and back travel of the pins 36 and 36' obviously corresponds to the forward and back travel of the pins 35 attached to the basket and by permitting the pins 36 and 36' to travel vertically between the chain wheels 39 and 40 the basket is permitted to remain stationary for a predetermined period at the rear ends of the tracks and prior to returning to its original position.

Obviously, as the lower front corners of the basket are forced rearwardly by the rods 34 and 34' the upper front corners thereof are caused to swing ahead by the action of the rollers in the tracks. The initial movement of the basket accordingly upends it in a rolling manner and the upending is gauged such that the basket will swing down in direct proportion to the speed at which the machine is being drawn ahead with the binding machine. After the basket has been upended it remains in that position and is given a rearward movement relative to the tracks such that it remains stationary in respect to the ground as the machine advances.

The shaft 41 is driven by the wheel 19 and the driving arrangement is such that the attendant on the binding machine can engage a clutch which will cause the shaft 41 to be driven and the basket operated in such a manner that after the basket has deposited the shock and returned to its original position the clutch aforesaid will be automatically disengaged to stop further movement of the basket.

This driving mechanism is now described: To the shaft 18' we secure a driving chain wheel 43 which is connected by a chain 43' to a chain wheel 44' secured to the end of a clutch shaft 44 suitably mounted on the front end of the machine. On the clutch shaft 44 we rotatably mount a chain wheel 45, suitable means being provided to prevent end movement of such wheel. The chain wheel 45 is connected by a chain 45' to a chain wheel 41' secured to the shaft 41. The chain wheel 45 is provided with a male clutch member 45' adapted to be engaged by a female clutch member 46' formed at the end of a sleeve 46 feathered on the clutch shaft.

An actuating lever 47 is pivotally connected to the beam 11 and extends forwardly and is attached to the sleeve in a manner such that the shifting of the lever moves the sleeve to bring the clutch members into or out of engagement. A rocking lever 48 is pivotally connected to the beam 10 and has one end attached to the forward end of the lever 47 and the other end turned forwardly. A pulling line 49 is connected to the forward end of the rocking lever and extends toward the binding machine, ter-

minating within convenient range of the attendant thereon. The latter arrangement is such that upon the attendant pulling the line toward the binding machine he will swing the lever 47 in a direction which will engage the clutch and consequently start the basket in motion. A spring 50 is associated with the rocking lever to normally maintain the clutch members disengaged. The automatic disengagement of the clutch members is effected by a connecting rod 51 attached to the rocking lever 48 and to a bell crank 52 pivotally mounted on the frame 24. One end of the bell crank is designed to be struck by a striking arm 53 secured to the chain 37 in a location immediately adjoining the pin 36. Obviously, upon the striking arm striking the bell crank it will cause the rod 51 to pull in a direction away from the binding machine and consequently effect through the rocking lever and the lever 47 the disengagement of the clutch members and such will occur due to the positions of the parts when the basket reaches its sheaf receiving position.

Forwardly of the basket we locate a butter which has the upper part 54 thereof stationary and the lower part 54' thereof adjustable and curving downwardly and rearwardly and terminating normally just nicely clear of the stubble of the field. By observing Fig. 4 it will be apparent that the lower edge of the portion 54' of the butter underlies the lower corner of the basket. The said butter actually receives the butts 100 of the sheaves deposited in the basket through the open top thereof.

The bottom or back of the basket is closed in the sheaf receiving position thereof by a pair of similar gates 55 and 56, these gates being pivotally carried by the lower or rear V-shaped basket frame. The gate hinge in each instance is formed by a rod 57 having the ends thereof bent at right angles to the body and flattened and riveted to the gate as indicated at 57' and 57''. The rod 57 is pivotally attached to the forward corner of the V-shaped under frame of the basket in each instance by a short hanger 58 and is also pivotally carried by a comparatively long arm 59 secured to the said basket frame. Actually, the rod 57 at each side of the basket is parallel to the meeting edges of the gates (see Fig. 7).

The gates, as hereinbefore intimated, are held closed in the sheaf receiving position of the basket and really support the sheaves directed into the basket through the open top thereof.

As the sheaves ejected from the deck of the binding machine have to be elevated so that they can be deposited into the basket or shock former we have provided an inclined elevator 60 which is suitably mounted on the side of the shocking machine adja-

cent the binding machine deck and is adapted to receive the sheaves discharged from the deck, elevate the same, and discharge them over a deflecting plate 61 into the basket. As elevators are customarily employed on shocking machines we have not considered it necessary to give a detailed description of the elevator used. Any suitable elevator will serve our purpose. The elevator, however, is only operated during the interval that the shock is being built in the basket. During the interval that the basket is moving the elevator is motionless. Means are provided and herein shown for automatically putting the elevator out of and into commission at the proper time, but as the same are not essential to the operation of the shocking machine itself we are not giving a detailed description thereof. Suffice it to say, that an elevator clutch 62 controls the elevator, this clutch being disengaged when the basket controlling clutch is engaged and vice versa.

The basket gates are controlled by the parts now described:

To each of the gate rods 57 we permanently connect a crank 63, the crank being supplied at the free end with a roller 63'. In the sheaf receiving position of the basket the rollers are engaged with the sides of the bars 14 and 15, these bars being for the greater part angle bars, but having parts of the horizontal flanges cut away as best shown in Figures 5 and 8 and the arrangement is such that the gates are held shut by them.

It is necessary in the back movement of the basket to maintain the gates locked for a period of travel and then to open them to allow the shock to pass out. The gates are retained closed in the original back going movement of the basket primarily by contact of the rollers with the bars 14 and 15 and then by engagement of the rollers with permanent rearwardly extending and upwardly inclining bars 64 and 64' suitably mounted on the shocking machine frame.

At the rear ends of the bars 64 and 64' we locate similar horizontally disposed plates 65 and 65' and these plates are provided each with a guide flange 66 in the form of an upstanding loop, one side of which is continuous with the vertical flange of the inclined bars 64 and 64' and the other end of which is spaced from the flange and deflect- ed inwardly. The flange 66 in each instance is formed to present two semicircular offsets 67 and 68 which are spaced somewhat apart and the offsets 67 control the opening of the gates and those 68 the closing of the gates.

On the plates 65 and 65' and directly opposing the offsets we mount similar double winged spring pressed guards 69 and 69'. These guards operate in the following manner. When the rollers 63' are moving back- wardly, the outer portions of the double

winged guards 69 prevent the passing rollers from entering the offsets 68 and the inwardly extending portions thereof swing back under the action of the moving rollers and allow the rollers to pass and also prevent them from entering the offsets 68. When the rollers have passed, the said guards 69 swing back to the position shown best in Figure 13 of the drawings. As the rollers move further back, they strike the inwardly extending portions of the wings 69' and are forced into the offsets 67. These offsets hold the rollers momentarily while the basket is still moving back and in so doing open the gates. In the continued back movement of the basket the rollers are pulled against the outer portions of the wings 69' and escape past and into the rear ends of the flanges 66, the wings 69' then resetting into the position shown in Figure 13 under the action of the springs 69".

On the reverse movement of the basket, the action is reversed, the rollers being prevented by the wings 69' from getting into the offsets 67 and being caused to travel into the offsets 68 by the wings 69. Having entered the offsets 68, the rollers act to close the gates and having closed them, the said rollers escape past the then outer portions of the wings 69 and thereafter the gates are held shut in the return movement of the basket by contact with the bars 64 and 64' and 14 and 15.

For convenience in description hereinafter we will consider the latter bars and the flanges 66 as controlling the guides for the gate cranks.

Referring now to the butter:

We might explain that the adjustable part or plate 54' thereof has the upper edge slidably located between a cross rod 70 and the lower edge of the stationary part 54 of the butter, the cross rod being carried by the forward ends of the tracks. The lower edge of the adjustable part of the butter is slidably mounted on a pair of rearwardly extending and downwardly inclining angle bars 71 and 71' permanently fastened to the machine frame.

The lower section or adjustable part of the butter is supported by upwardly extending links 72 and 72' pivotally attached thereto and having their upper ends pivotally connected to cranks 73' and 73" carried by an elevated cross shaft 73' supported by the brace bars 23 and 23'. Operating levers 74 and 74' are secured to the ends of the shaft 73 and the levers 74 and 74' are connected by adjusting rods 75 and 75' to the track extensions.

The rods 75 and 75' are provided with adjusting openings and bolts pass through these openings and form an adjustable connection with the track extensions. Obviously, by adjusting the rods 75 and 75' one can extend or withdraw the movable or lower section of the butter, the adjustment being

made to accommodate the nature of the grain, that is, whether the sheaves be long or short.

In connection with the upper part of the butter we also utilize a spreading arm or kicker 76 which is located centrally and immediately to the rear of the stationary part of the butter and is carried by a shaft 76' rotatably mounted in a carrying bearing secured to a transversely extending angle bar 76^x which reinforces both the track extensions and the stationary part of the butter.

The forward end of the shaft 76' is provided with a crank 76^z and this crank is reciprocated backwardly and forwardly by a pitman 77 actuated by a crank 77' located at one end of the upper elevator shaft 77^x.

According to the above connections it will be obvious that when the elevator is operating the kicker will be reciprocated and will act to throw to the sides or spread the butts of the sheaves being deposited in the basket. This naturally aids in providing a well spread base to the shock being formed.

As part of the basket equipment we provide prongs which are closed in to grip the head of the assembled shock and which hold the heads for a predetermined period and then open to clear the deposited shock.

These prongs and the manner in which they are operated are now described:

The basket frames carry rotatably mounted opposing shafts 78 and 78' to which we secure substantially U-shaped sets of prongs 78^x, the prongs in the normal or shock forming position of the basket being out and being later designed to pass in through suitable openings 78^z provided in the sheet metal sides of the basket. The prongs are positioned such that they will pierce the sheaves in a location slightly above the customary tie string or band. The sets of prongs operate together, each of the shafts 78 and 78' being provided with a crank 79 and the cranks are connected pivotally by links 79' to a rocker lever 79^x pivotally carried by a bracket arm 79^z secured to the T-bar 28.

The arrangement of the latter parts is such that when the shaft 78 is oscillated a similar oscillation will be produced in the shaft 78' and the sets of prongs will have identical movements.

In order to control the shaft 78 and in so doing move the prongs at the proper time we have supplied the parts now described:

Adjacent the rear end of the beam 5 we locate an upstanding post 80 which supports the rear end of a horizontally disposed bar 80', the forward end of which is fastened to the track extension 20'. The bar 80' supports a horizontally disposed stationary track 81 more or less of a channel iron cross section and provided with inturned flanges 81^z and 81^x. This track is of predetermined length and has the ends thereof closed and in

it we locate a small four wheeled traveller or carriage 82 which operates on the flanges 81^z and 81^x and is provided with a downwardly extending arm 82'. This arm is permanent in respect to the carriage, but moves forwardly and backwardly with the same. To the lower end of the arm we permanently fasten a horizontally disposed bar 83 which has the forward end extending beyond the bar 82' and the rear end located behind the same and downturned. A pair of diverging coiled springs 84 and 84' are secured to the bar 83, one in advance, and the other to the rear of the bar 82' and are also attached to the front end of the basket. To the downturned end of the bar 83 we pivotally connect a bell crank 85 to the ends of which we pivotally attach a long and a short link, the long link 85' being pivotally fastened to the upper forward corner of the basket at 85^z and the shorter link 85^x being pivotally attached to the lower end of a rocker arm 86, the rocker arm being pivotally carried by a bar 86' permanently secured to the basket side. The upper end of the link 86 is connected by means of an operating rod 87 to the crank 79 at that side of the basket.

As before stated, in the shock forming position of the basket the prongs are out and the latter prong controlling parts are in relative positions as best shown in Fig. 2. As the basket starts to turn under the influence of the rods 34 and 34' the pivot point 85^z moves ahead which movement causes a back swing of the lower end of the bell crank 85, it being understood at this time the carriage 82 is at its forward point of travel, with the result that any advance movement of the point 85^z effects the swinging of the bell crank. The bell crank in so moving operates the rocker arm 86 which acts, through the rod 87, to pull down on the crank 79 and by so doing simultaneously produces an in-moving of the sets of prongs. Accordingly, the head of the assembled shock is pierced by the prongs from opposite sides. The prongs hold the shock during the following movement of the basket and do not fully swing out until such time that the carriage 82 has reached its back point of travel. When the carriage reaches this latter position it is stopped, but the basket still has a rearward movement of limited extent and this extra movement of the basket effects through the connections shown the swinging of the bell crank in a direction which will withdraw the prongs and entirely free the shock therefrom. In the return movement of the basket the prongs close in as the basket approaches its initial position but open out to the original position prior to the basket finally reaching the original sheaf receiving position.

The basket is provided with a hinged top 88 which is held open in the sheaf receiving position of the basket by a crank 88', the

crank engaging with a stationary trip bar 88¹ permanently secured to the track extension 20', the arrangement being such that the top is held normally vertical in the sheaf receiving position of the basket. A second crank 88² is also associated with the top and to the latter crank we connect a comparatively strong spring 89 which is suitably anchored to the basket frame and operates to close the hinged top as the crank 88¹ passes away from the trip bar in the movement of the basket and thereafter maintains the top closed until the basket returns to its original position.

15 Within the basket we pivotally mount a substantially U-shaped bale bar 90 which is located such that it will receive, support and draw together the heads of the sheaves deposited in the basket and later, during the 20 depositing of the shock, will steady the same. A crank 91 is connected to the bale bar and the lower end of the crank is connected by a cable or pulling line 92 to the upper stationary part of the butter.

25 The arrangement of the crank and pulling line is such that there is no movement of the bale bar effected until the basket is approaching its rear position of travel, at which time the pulling line tightens and 30 produces a swinging movement of the crank 91 in a direction which will raise the bale bar to pass it away from the deposited shock and clear it over the head of the same.

In order to better understand the general 35 operation of the machine we will now give a short description of the various parts, assuming that the shock has been built in the basket with the butts engaging the butter and the head of the shock built in the bale 40 bar.

The attendant pulls the line 49 which acts to stop the conveyor and start the working parts of the shocking machine in motion. The basket turns ahead and in the initial 45 turning movement the prongs close in and pierce the head of the shock, not only holding it, but crowding it together, and the basket top closes. In the initial movement of the basket the heel or then lower portion 50 of the shock engages the stubble of the field and in the subsequent movement of the basket the butt of the shock is virtually rolled ahead into the stubble and whilst being maintained otherwise relatively stationary 55 in respect to the ground.

We particularly wish to emphasize the feature that from the time the heel of the shock engages the ground the said shock is maintained, in the subsequent operation and 60 until it is finally released, stationary in respect to the field, the machine advancing.

The prongs remain in the shock until the basket has almost reached its rear point of travel, being withdrawn after the traveller 65 82 has struck the rear end of the track and

during the further rearward movement permitted the basket as hereinbefore explained. The gates are arranged so that they are timed to open prior to the prongs being released from the shock and the bale bar is 70 controlled so that it lifts from the deposited shock coincident with the release of the prongs. As the bale bar raises clear the deposited shock is entirely free. In the reverse movement of the basket the various 75 moving parts are manipulated to assume their original positions when the basket reaches its original sheaf receiving position and at the time it reaches this position the top 88 has been opened and the clutch controlling the basket is automatically thrown out of commission and the elevator thrown into action.

In order that the movement of the basket may be clearly understood we have indicated 80 in dotted outline on Figure 4 of the drawings, the approximate path of travel of a selected point of the shock, the selected point being the centre of the shock.

Considering the selected centre point to 85 be at 93 Fig. 4, when the basket is in the sheaf receiving position, then this selected centre point will travel in the path shown in dotted outline where it will be observed that it initially moves up and ahead, then turns 90 down and thereafter gradually swings rearwardly and downwardly until a horizontal direction of travel is reached. The movement so given the basket permits it to deliver the sheaf onto the ground in a 100 natural forward rolling manner and whilst maintaining the shock relatively stationary in respect to the ground. Obviously, if no initial up movement of the shock centre were permitted the engaged heel thereof 105 would cause an end shifting of the shock in the basket which would produce an angular base thereto instead of a flat base as is desired.

What we claim as our invention is:— 110

1. In a shocking machine, the combination with a suitable supporting frame, of opposing parallel tracks permanently mounted on the frame and extending lengthwise thereof and having their forward 115 ends turned upwardly to provide curved track extensions, a sheaf receiving normally horizontally disposed and shock forming basket having the butt or large end thereof directed forwardly, carriers secured to the large end of the basket at the upper and lower sides thereof, said carriers operating in the tracks and track extensions, and means for moving the basket to cause it to travel in a fixed path, as determined by the tracks and track extensions. 120

2. In a shocking machine, a shocking machine frame, a pair of spaced parallel tracks mounted on the frame and extending lengthwise thereof and having their forward ends 125

curving initially upwardly and then rearwardly, a normally horizontally disposed sheaf receiving and shock forming basket, upper and lower sets of carriers secured permanently to the forward end of the basket, the said carriers operating on the tracks and controlling the position of the basket, and means for moving the basket on the tracks to turn the same forwardly and upend the shock.

3. In a shocking machine, a shocking machine frame, a pair of spaced parallel lengthwise extending stationary tracks mounted on the frame and having their forward ends curving initially upwardly and then rearwardly, a normally horizontally disposed sheaf receiving and shock forming basket, upper and lower carriers secured to the forward end of the basket, said carriers operating in the tracks, operating means connected to the front end of the basket at the bottom and adapted to move the basket initially rearwardly and subsequently forwardly, gates normally closing the bottom of the basket, means for opening the gates as the basket approaches its rearward point of travel, a butter carried by the frame and located at the front end of the basket, sets of prongs carried by the sides of the basket, and means for closing in the prongs to pierce the head of the assembled shock and during the initial turning movement of the basket and to withdraw the prongs immediately after the gates have opened.

4. In a shocking machine, a shocking machine frame, a pair of spaced parallel lengthwise extending stationary tracks mounted on the frame and having their forward ends curving initially upwardly and then rearwardly, a normally horizontally disposed sheaf receiving and shock forming basket, upper and lower carriers secured to the forward end of the basket, said carriers operating in the tracks, operating means connected to the front end of the basket at the bottom and adapted to move the basket initially rearwardly and subsequently forwardly, gates normally closing the bottom of the basket, a normally open top carried by the basket, means for closing the top as the basket begins to move and for subsequently holding the top closed until the basket is returning to its original sheaf receiving position, means for opening the gates as the basket approaches its rearward point of travel, a butter carried by the frame and located at the front end of the basket, sets of prongs carried by the sides of the basket and means for closing in the prongs to pierce the head of the assembled shock and during the initial turning movement of the basket and for withdrawing the prongs immediately after the gates have opened.

5. In a shocking machine, a normally

horizontally disposed sheaf receiving and shock forming basket having an entrance opening in the top thereof, a substantially U-shaped bale bar carried by and pivotally mounted in the basket and on which the heads of the sheaves are built, and means for swinging the bale bar away from the heads of the sheaves subsequent to the shock contained within the basket being deposited on the ground in an upstanding position.

6. The combination with a sheaf receiving and shock forming basket, said basket having a sheaf entry opening in the top thereof, of a bale bar carried by and located within the basket and adapted to receive and support the heads of the sheaves deposited in the basket and to crowd the heads of the sheaves together.

7. In a shocking machine, the combination with a machine frame, a normally horizontally disposed sheaf receiving and shock forming basket carried by the frame and means for forwardly turning the basket to upend the contained shock, of a butter located at the forward end of the basket and engaging the butt of the formed shock, sets of prongs carried by the basket and means for operating the prongs to close them in to pierce the head of the shock during the initial turning movement of the basket and to hold the shock after the butt thereof leaves the butter.

8. In a shocking machine, the combination with a shocking machine frame and a normally horizontally disposed sheaf receiving and shock forming basket carried by the frame, of a butter carried by the frame and located at the forward end of the basket and presenting an upper stationary section and a lower adjustable section.

9. In a shocking machine, the combination with a shocking machine frame and a normally horizontally disposed sheaf receiving and shock forming basket carried by the frame, of a butter carried by the frame and located at the forward end of the basket and presenting an upper stationary section and a lower rearwardly extending and downwardly curving adjustable section which can be extended or withdrawn in respect to the stationary section.

10. In a shocking machine, the combination with a shocking machine frame, of a pair of spaced parallel lengthwise extending tracks permanently mounted on the frame, said tracks having their forward ends curving upwardly, a normally horizontally disposed sheaf receiving and shock forming basket, upper and lower pairs of travellers permanently secured to the front end of the basket and adapted to operate in the tracks and normally located in the forward curved ends of the tracks, similar endless side chains mounted on the shocking machine frame, clutch controlled means for simultaneously

driving the chains and basket operating rods connecting the chains to the front end of the basket at the bottom.

11. In a shocking machine, the combination with a shocking machine frame, of a pair of spaced parallel lengthwise extending tracks permanently mounted on the frame, said tracks having their forward ends curving upwardly, a normally horizontally disposed sheaf receiving and shock forming basket, upper and lower pairs of travellers permanently secured to the front end of the basket and adapted to operate in the tracks

and normally located in the forward curved ends of the tracks, similar endless side chains mounted on the shocking machine frame and in advance of the basket, said chains having vertically extending portions located rearwardly, clutch controlled means for simultaneously driving the chains and operating rods connecting the chains with the forward end of the basket at the underside. 15 20

Signed at Winnipeg, this 14th day of March, 1922.
